United States Patent Office.

MARTIN LANDENBERGER, OF PHILADELPHIA, PENNSYLVANIA.

Design No. 4,235, dated July 19, 1870.

DESIGN FOR A SHAWL.

The Schedule referred to in these Letters Patent and making part of the same

---

To all whom it may concern:

Be it known that I, MARTIN LANDENBERGER, of Philadelphia, in the county of Philadelphia and State of Pennsylvania, have invented and produced a new and original "Design for Shawl or other Woven Garment," of which the following is a specification.

The design is fully represented in the accompanying drawing.

A is a border of mixed threads; then follows a plain stripe, B; then a stripe composed of three narrow bands, C C C, twilled, so as to form the oblong figures *a*, of a color distinct from that of the intervening portion of the fabric between their edges; then a

plain stripe, B, again; and then three longitudinal mixed stripes, D D D, and a plain stripe, B.

The surface of the entire fabric is raised, forming somewhat like diamond-shaped stitches.

What I claim is—

The design for shawl, as shown and described.

In testimony whereof I have signed my name to this specification in the presence of two subscribing witnesses.

MARTIN LANDENBERGER.

Witnesses:

J. M. MASON,
C. L. EVERETT.
